[57] CLAIM

The ornamental design for a housing for a digital clock
or the like, as shown and described.

DESCRIPTION

FIG. 1 is a front perspective view of a housing for a
digital clock or the like, showing my new design;

FIG. 2 is a front elevational view thereof;

FIG. 3 is a right-side elevational view thereof, the left
side being a mirror image thereto;

FIG. 4 is a top plan view thereof; and

FIG. 5 is a cross-sectional view of FIG. 2 as taken from
line 5—5.
